AUTOMATIC CUSTODY TRANSFER OF CRUDE OIL

Marvin A. Remke and Louis E. Kuntz, Bartlesville, Okla., assignors to Phillips Petroleum Company, a corporation of Delaware

Filed Aug. 18, 1958, Ser. No. 755,851

9 Claims. (Cl. 210—84)

This invention relates to the automatic transfer of liquids. In one aspect, it relates to automatic transfer of measured volumes of liquid of predetermined quality. In another aspect it relates to automatic transfer of measured volumes of crude oil of predetermined quality as regards B.S. & W. (basic sediment and water) content.

This application is a continuation-in-part of our pending application, Serial No. 686,255, filed September 25, 1957, now abandoned.

The pumping, transporting, treating and storing of crude oil on the lease have been made automatic to various degrees in recent years. However, the measurements and handling required for the sale or custody transfer of crude oil have not changed to any great extent until quite recently.

The terms lease automatic custody transfer, lease automatic transfer, automatic transfer or automatic transfer system as used throughout this specification and claims, are used synonymously and interchangeably, and are intended to mean any system, process carried out thereby, or apparatus particularly adapted for use therein and comprise automatic means to inspect a liquid for the presence of a predetermined undesirable amount of at least one selected undesirable constituent, and automatic means to reject the liquid when said constituent content is above said amount, to meter accurately said liquid when said constituent content is below said amount and pass the inspected and metered liquid to a dispensing line, and subcombinations thereof, such as metering means, inspection means, treating means, pumping means, valving means and automatic control means particularly adapted for use therein, and processes carried out thereby. In the general system, if desired, there is also included automatic means to treat the liquid to remove the undesired constituent before said inspection, and/or automatic means to recycle said liquid when rejected to said treating means. Furthermore, the automatic means to reject contaminated liquid, that is, liquid containing more than the predetermined undesirable amount of the undesirable component, are provided to operate continuously except as interrupted by automatic operation of the system.

The term custody as used in conjunction with lease automatic custody transfer is intended to convey the meaning of the transfer of a liquid, for example, from one owner to another owner. For example, it refers to the transfer of crude oil from the producer to a purchaser.

In this specification we will describe our apparatus and process as applied to the automatic transfer of measured volumes of crude oil of predetermined quality as regards B.S. & W. merely as an example of our process and apparatus. It is realized that measured volumes of other liquids of predetermined quality can be transferred by our apparatus according to the method disclosed herein, such as refined oils, natural gasoline, hydrocarbon products in process, finished hydrocarbon products, and such other hydrocarbon liquids as might be desired to be substantially continuously transferred.

2

The sale of crude oil requires that temperature, volume, A.P.I. gravity and B.S. & W. content of the oil be known and recorded on a "run" ticket. In manually operated transfer systems, these measurements are usually made manually by a pumper who represents the crude oil producer and independently by a gauger who represents the crude oil pipe line purchasing company in case the oil is sold to a pipe line company for transportation. These men obtain samples of the oil from tanks through thief hatches. Tanks are gauged by reading the oil level to the nearest $\frac{1}{8}$ inch on a gauge stick lowered through the hatch. Temperature is measured by lowering a specified type of thermometer through the hatch into the oil, then removing the thermometer and quickly observing the temperature. A.P.I. gravity is measured by use of a hydrometer in a sample of the oil obtained by use of a special sample "thief." The purity of the oil as regards B.S. & W. is determined by centrifuging a measured volume of the oil from the sample thief.

When these properties of the oil are determined manually, samples are taken through sample hatches and each time a sample hatch is opened vapors are lost.

One object of the present invention is to determine and record the temperature of the crude oil automatically and without loss of vapors through opened thief hatches.

Another object of this invention is to provide a system for metering crude oil and for transferring the metered oil to a point of disposal, the system being entirely automatic and free from errors inherent with manual operation.

Still another object of this invention is to provide a fully automatic and substantially continuous system for metering and transferring of quality crude oil with the system being operated without personal attention other than occasional maintenance and changing of recorder charts and the like.

Yet another object of this invention is to provide such a system which is foolproof and failure-proof so that neither the oil producer nor the pipe line company can be shorted by mishandling of the oil.

Still other objects and advantages of this invention will be realized upon reading the following specification and drawing, which describes and illustrates, respectively, preferred embodiments of our invention.

One advantage of our automatic transfer system is that there is less evaporation loss of the crude oil transferred than when manually transferred, which is a direct saving in volume as well as in quality of the oil because vaporization losses are always losses of the light ends. In one instance, according to our invention, the custody transferred crude oil had an A.P.I. gravity 0.2° higher than the oil transferred by a manually operated transfer system. This 0.2° A.P.I. gravity represents 0.5 percent volume, or, in other words, 5 barrels crude oil saved per 1,000 barrels crude oil transferred.

Figure 9 illustrates a modification of a portion of the apparatus of Figure 1.

Considerably less steel is required for building our automatic custody transfer system than a manually operable system of the same capacity because fewer temporary storage tanks are required. This saving in steel also means smaller capital investment.

Our invention specifically comprises a system for transferring known volumes of hydrocarbon liquid of predetermined quality from a source to a point of disposal comprising, in combination, a treating vessel for said hydrocarbon liquid, a surge vessel for receiving treated hydrocarbon liquid, a meter vessel, first and second conduits communicating said treating vessel with said surge vessel, a first pump in said second conduit, a third conduit communicating said surge vessel with said meter vessel, a second pump in said third conduit, a fourth conduit communicating said meter vessel with a point of disposal, a monitor assembly for controlling quality of hydrocarbon liquid, said monitor assembly comprising a monitor for sensing B.S. & W. content of the hydrocarbon liquid, means for passage of hydrocarbon liquid from said surge vessel to said monitor and return to said surge vessel, first and second motor valves in said second and third conduits, respectively, a first electrical circuit communicating said monitor with said first pump and with said first motor valve, a second electrical circuit communicating said monitor with said second pump and with said second motor valve, said monitor assembly being adapted to close said second motor valve and to close off electric current to the motor of said second pump to stop same and to open said first motor valve and to close the circuit to the motor of said first pump to start same when said monitor senses a B.S. & W. content in the hydrocarbon liquid flowing therethrough higher than a predetermined B.S. & W. content.

Furthermore, our invention comprises a method for transferring a known volume of a hydrocarbon liquid having less than a predetermined concentration of B.S. & W. to a point of delivery, comprising the steps of receiving said liquid containing B.S. & W. in a receiving zone, treating said liquid in said receiving zone to remove said B.S. & W., withdrawing an aqueous phase from said receiving zone, passing liquid of reduced B.S. & W. content to a surge zone, maintaining the B.S. & W. content of said liquid in said surge zone below a predetermined value by recycling liquid containing a greater B.S. & W. content than said predetermined content from said surge zone to said receiving zone, passing only liquid having a less B.S. & W. content than said predetermined content to a metering zone of predetermined volume until said metering zone is completely full, then passing said liquid from said metering zone to said point of delivery.

While the terms probe and float, or liquid level float, are used in this specification and claims as liquid level sensing means, they are described herein merely as examples of suitable liquid level sensing means. Any other suitable type of liquid level sensing means can also be used in the transfer system of our invention.

In the operation of the transfer system of our invention, produced oil enters our system, from a source not shown, via pipe 11. From this pipe oil flows into a vertical pipe, commonly called a "boot" in which gas and water are allowed to separate from the oil. The separated gas is discharged from boot 14 through an equal-

izing line 18 to a vent, flare, or gathering system, not shown. Oil and water are discharged from the bottom of the boot into the bottom of a receiver tank 13a in which separation of oil and water is obtained. The separated water settles to the bottom of receiver tank 13a and is drawn off through a pipe 12 to such disposal as may be desired. A water level is maintained in the receiver tank for some distance above the level of pipe 12, so that the oil entering from the boot passes upwardly through a layer of water to cleanse it of impurities and to reduce or break any emulsion present to the basic components of oil and water. If desired, heat is applied to the water section of the receiver to assist in breaking emulsion that may be present. Clean, treated oil passes from the receiver tank through a pipe 20 into a surge tank 15. As illustrated in the drawing, there is a single surge tank, but it is to be understood that more than one surge tank is used, if needed.

As the oil enters surge tank 15 and the oil level begins to rise, a float actuated switch FS-6 operates to start a monitor pump 28 which circulates surge tank oil through a pipe 21, a pipe 27 containing a B.S. & W. monitor cell 29 and back to the surge tank. The monitor cell 29 is preferably a capacitance cell in which the liquid being measured is the dielectric. A capacitance cell suitable for use as herein disclosed is described in a copending application, Serial No. 686,192, filed September 25, 1957. It is preferable that the capacitance cell be calibrated in percent B.S. & W. so that if the B.S. & W. content of the crude oil circulating through the monitor cell reaches a predetermined high limit, such as 0.5 percent, a motor valve V-3 opens and a circulating pump 25 starts. Oil having B.S. & W. content of 0.5 percent and higher (bad oil) is then returned to the boot 14 for retreatment. The apparatus, described hereinafter, which operates to open valve V-3 and to start the circulating pump 25 in response to high B.S. & W. content oil passing through the monitor, overrides all other operations so that detection of bad oil shuts down the transfer portion of the system. When oil containing less than 0.5 percent B.S. & W. is considered acceptable by the oil purchasing pipe line company, then such oil is hereinafter referred to as merchantable oil. The monitor 29 maintains valve V-3 open and pump 25 operating until the oil has been sufficiently retreated and is merchantable, at which time V-3 closes and the circulating pump 25 is stopped. If, however, the oil does not clean up, continued oil production fills the surge tank 15 to an emergency high level indicated by the level of a probe J-8. At this emergency high level, a signal will be given at a convenient location for notification of a pumper, or otherwise calling for help. In some instances, the actuation of J-8 closes valves to stop flow of lease oil to the treating system. As long as merchantable oil is passing through the monitor cell, the latter will permit normal operation of the metering and transfer system.

While the crude oil treating system herein described comprises a receiver tank 13a and boot 14, other suitable emulsion treating or dehydration systems in common use commercially are, in some instances, used with our transfer system.

Continued passage of merchantable oil through the monitor cell indicates that the surge tank 15 contains merchantable oil. Filling continues to a level identified by the level at which a probe J-7 is installed in the tank. When the oil reaches the level of the probe J-7, a valve V-15 is opened and a transfer pump 26 starts and merchantable oil is transferred from the surge tank through pipes 21, 22 and 23a into a meter tank 16. If the oil level in the surge tank falls to the low level indicated by the float actuated switch FS-6, this switch operates to stop the transfer pump 26. The pump remains inoperative until such time as the merchantable oil level again reaches the level of probe J-7. When probe J-7 is again wet, the transfer pump 26 starts. This pump continues

to transfer merchantable oil into the meter tank 16 until oil wets a probe J-13 at which time the wet probe causes valve V-15 to close, transfer pump 26 to stop and a one-minute delay period to start for venting of gas evolved from the oil through a gas equalizing line 18. At the end of this delay period a valve V-14 opens for drainage of oil from outside rim 16a in the dome portion 16b of the tank (Figure 3). When the oil level reaches that indicated by probe J-14, i.e., when the oil level in the dome 16b is below rim 16a, a valve V-16 in pipe 31 opens, and a pipe line pump 33 starts. As valve V-16 opens and with a second meter tank 17 dry, a valve V-25 opens and the transfer pump 26 starts thereby starting transfer of merchantable oil from surge tank 15 to the meter tank 17. The same cycle as regards filling of the meter tank 17 takes place as that which took place as meter tank 16 was filling. Meter tank 17 is thus provided with probes J-23, J-24 and J-27, in locations corresponding to locations of probes J-13, J-14 and J-17 of tank 16.

After a sufficient length of time has elapsed for probe J-14 in the full meter tank 16 to become dry, by drainage of oil through a valve V-14, the dry probe J-14 then causes valve V-14 to close, valve V-16 to open and the pipe line pump 33 to start. The pipe line pump continues pumping until probe J-17 becomes dry at which time valve V-16 closes and the pipe line pump is shut down. It is intended that the meter tank 17 be filled, and excess oil over the measured tank volume be drained off through valve V-24 and this tank of oil prepared for delivery to the pipe line by the time the meter tank 16 is empty and valve V-16 closed. As probe J-17 in meter tank 16 becomes dry, valve V-24 can be closed and valve V-26 opened and the pipe line pump 33 will continue to run. In this manner there is substantially continuous transfer of oil to the pipe line until such time as the supply of merchantable oil in the surge tank is depleted.

In Figure 2 is illustrated a portion of the electrical system employed in the practice of our invention, while Figures 2A and 2B illustrate detailed wiring and actuation of the various relays in operating the several valves and pumps in response to liquid levels in the vessels as sensed by probes, floats, and other sensing apparatus. The electrical system will be described in conjunction with the functioning of each element of the system following the general operational outline as given hereinbefore.

This description will begin with the surge tank 15 of Figure 1 being empty, the control system of Figures 2, 2A and 2B being de-energized, all latching relays being in their unlatched position, all motor valves V-3, V-14, V-15, V-16, V-24, V-25 and V-26 being closed and the meter tanks 16 and 17 being empty. A complete normal cycle will be hereinafter outlined. In Figure 2A the following are toggle switches and are closed: the emergency shut down switch SW-1, sequence interrupter switch SW-2, pipe line pump stop switch SW-6 and monitor pump "stop" switch SW-10.

Closing a 3-phase master switch MS energizes the primary winding of a 2 k.v.a. transformer 101 which is connected across lines L₁ and L₂ of the 3-phase 440-volt electrical power supply. The coil of a relay R-6, connected across lines L₂ and L₃, is also energized. This relay protects the motors from single phase operation by opening a contact R-6A thereby breaking contact between TD-1A and R-1 when line L₃ is open. If line L₁ or L₂ is open, the control circuit will be dead because there is no voltage across the primary coil of the transformer 101. A relay R-7 will be energized to connect the recorder and time clock TC-1 (Figure 2) to the control voltage and disconnect it from a stand-by battery 102.

All motor starters, including the pipe line pump starter, have 110 volt coils and are operated directly from the control system. The chart drive motor in the temperature and pressure recorder 37 (Figure 2) and the motor in the time clock TC-1 are across the control transformer

secondary winding ahead of a master control switch MCS. These motors will then run continuously on 110 volts A.C. or from the stand-by storage battery 102 which is connected automatically by operation of relay R-7 in case power from lines L₁ and L₂ fails. TC-1 is a 24 hour clock which is preset to open a contact TC-1A at 7:45 a.m. and close it at 8:15 a.m. This opening and closing of contact TC-1A allows completion of the "run" in progress and stops the pipe line pump as required by the pipe line company for taking their daily inventory.

Closing the master control switch MCS energizes the electronics of the water detecting monitor 29, the probe level control devices J-7, J-8, J-13, J-14, J-17, J-23, J-24 and J-27 and the coil of a time-delay relay TD-1. A latching relay LR-8 is energized through a low contact FS-6L of a float actuated switch FS-6 in the surge tank 15. Energized relay LR-8 then opens a contact LR-8A. During the delay introduced by the time-delay relay TD-1, the level control electronics and monitor electronics will be warmed up to operating temperatures and all probe relay contacts will assume their operating positions, i.e., all "L" (low) contacts are closed and all "H" (high) contacts opened.

Contact R6-A and the emergency shut down switch SW-1 are closed so that closing of a switch TD-1A energizes a relay R-1 which then closes a contact R-1A to energize the meter tank control system. Since at the beginning of the operation the surge tank 15 is empty, probe J-8 (a capacitance probe) is dry, high contacts of probe J-8 are open, thus de-energizing an emergency pilot light on a panel board in a control house, and at a telephone P.B.X board at a convenient location. The J-8 contact serves as a power failure signal at the telephone P.B.X board as well as emergency high.

A time-delay relay TD-3 is operated by the monitor and is de-energized when the water content of the crude oil passing through the monitor cell is within the allowable limit. The time-delay of relay TD-3 is set at a predetermined time, as, for example, 30 seconds, until operating experience dictates otherwise. This delay is to delay operation of the "bad oil" (water content higher than 0.5 percent) sequence when transient drops of the water have caused the motor to read above 0.5 percent (above a predetermined set limit of water content). For the following description, it is assumed that the monitor cell, which also is a capacitance cell, is filled with air, as on initial start up, or with merchantable oil. In either case the relay TD-3 is de-energized and the contacts controlled thereby are open or closed as illustrated in Figure 2B.

The next step is to start passage of crude oil from receiver tank 13a through pipe 20 into surge tank 15. When sufficient oil has entered the surge tank, the float of the float actuated switch FS-6 rises and the switch closes a contact FS-6H to close a circuit to start the pump 28 for circulation of oil from the surge tank through pipes 21, 27 and the monitor cell and return to the surge tank. Closing of the circuit through the monitor pump 28 closes contact MP-A. Since the high level contact FS-6H of the float switch FS-6 was closed, obviously the low level contact FS-6L is open. Latching relay LR-8 remains latched with contact LR-8A remaining open. Oil is now being circulated from the bottom of the surge tank 15 through the monitor cell 29 and returned to the surge tank.

Continued passage of oil from receiver tank 13a to the surge tank 15 raises the oil level, and finally the level reaches the (normal high) capacitance probe J-7 and at this time transfer of oil to meter tank 16 begins. The necessary circuits completed for transfer of oil from the surge tank to meter tank 16 are as follows: Probe J-7 (in the surge tank) becomes wet, latching relay LR-8 unlatches and contact LR-8A closes; latching relay LR-1 latches to open contact LR-1A and to close contact LR-1B. When contact LR-1A opens, relay TD-4 energizes and contact TD-4A opens and motor valve V-14 closes. The closing of contact LR-1B, just mentioned, opens

valve V-15, contact V-15-A closes and the transfer pump 26 starts thus pumping oil from the surge tank 15 to meter tank 16. Upon closing contact V-15-A, contact V-15-B opens and interlocks with valve V-16 so that oil cannot under any conditions leave the meter tank while oil is being admitted thereto.

It is intended that oil is to be transferred from the surge tank to either meter tank at a slightly greater rate than the oil enters the surge tank through pipe 20 from the receiver tank 13a. Upon continued passage of oil from the surge tank to meter tank 16, the oil level in the surge tank drops below probe J-7 and the high contact of probe J-7 opens with no effect on the circuits set up by it through latching relays LR-8 and LR-1.

While meter tank 16 is filling, probe J-17 is wet and its relay JR-17 opens switches JR-17-L1 and JR-17-L2 with no effect on the system. When meter tank 16 becomes filled, the probe J-14 becomes wet, and the relay JR-14 operates to open contact JR-14-L1 with no effect on the system. When the contact JR-14-L1 is opened, contact JR-14-H1 is closed, also with no effect on the system. At the same time contact JR-14-H2 closes which operation latches latching relay LR-2 and contact LR-2A is closed which operation merely prepares the circuit to V-16. Contacts JR-14-H1 and JR-24-H1 are connected across the contact LR-8A to prevent incomplete operation of the system in the event that the surge tank level drops the float on float operated switch FS-6 when the level in the meter tank being filled is between J-14 and J-13 or between J-24 and J-23, depending upon the meter tank being filled. For example, if meter tank 16 is being filled and probe J-14 has just become wet as the surge tank became empty, the low contact FS-6L of the float switch FS-6 closes, latching relay LR-8 latches contact LR-8A opens and the transfer pump 26 stops. If the level of oil in meter tank 16 should drop sufficiently for any reason whatever and probe J-14 should become dry the circuit would be set up for running meter tank 16 to the pipe line but since probe J-13 had not been reached by the oil, the operation would be incomplete. The shunting contact JR-14-H1 will prevent the stopping of the transfer pump until the top probe J-13 has been reached by oil even though the float switch has operated and contact LR-8A has opened. When the top probe J-13 is reached by the oil, the transfer pump 26 will stop as usual but will not restart until the surge tank level reaches the level of the probe J-7. Meter tank 16 will run to the pipe line when meter tank 17 is empty and both meter tanks will be empty until the surge tank is filled to the normal high level.

When meter tank 16 becomes full, oil to this tank is, of course, stopped and its passage started to meter tank 17. Thus, when probe J-13 in the top of meter tank 16 becomes wet, the relay JR-13 of probe J-13 operates to open switch JR-13L with no effect on the system other than protecting latching relay LR-1 from cycling. Switch JR-13H also closes and latching relay LR-1 unlatches and contact LR-1B opens which latter operation closes valve V-15, opens contact V-15-A which operation stops transfer pump 26 and closes contact V-15-B which interlocks with valve V-16. As contact LR-1B opens, contact LR-1A closes and time-delay relay TD-4 energizes, contact TD-4A closes thereby opening valve V-14 after a one-minute time delay. As contact LR-1A closes, latching relay LR-6 latches and contact LR-6A opens thereby charging condenser Z-1 through the 22K resistor in series with rectifier X-1 (Figure 2a). Latching relay LR-3 also latches and contact LR-3B closes thereby opening valve V-25 and closing contact V-25-A with the simultaneous starting of the transfer pump 26. As contact LR-3B closes, contact LR-3A opens and de-energizes time-delay relay TD-5 which opens switch TD-5A thereby closing valve V-24. Oil is now being transferred to meter tank 17. On succeeding cycles one meter tank will still be running to pipe line when the

other has filled. The transfer pump 26 will stop and not restart until one tank is completely empty and its pipe line valve has closed.

The topping-out of meter tank 16 involves wetting of probe J-13, then after the aforementioned one-minute time delay for gas-venting, valve V-14 is opened thereby allowing oil from the dome 16b of tank 16 to drain through valve V-14 and pipe 19 to the surge tank. During the topping-out operation, probe J-13 becomes dry thereby causing relay JR-13 to open switch JR-13H with no effect on the system. At the same time contact JR-13L closes, also with no effect on the system. As probe J-14 becomes dry, in the topping-out of meter tank 16, the probe relay JR-14 operates to open contact JR-14-H1 and to open contact JR-14-H2, both with no effect on the system. At the same time contact JR-14-L1 closes and valve V-16 opens. At the time valve V-16 opens contact V-16-A closes thereby causing the following operations to occur: valve V-16 relay VR-16 energizes thereby opening contact VR-16-A which interlocks with valve V-15; contact VR-16-B opens which interlocks with valve V-26; and contact VR-16-C closes thereby energizing time-delay relay TD-2 which closes contact TD-2A and starts the pipe line pump 33.

A pressure switch 34 is provided in the pipe line on the discharge side of pipe line pump 33 and is set to prevent starting of the pipe line pump in case the pipe line pressure is higher than a predetermined pressure. If desired, the pressure switch 34 is arranged to give a signal when a pipe line pressure greater than the predetermined pressure is reached.

When oil from the surge tank 15 starts into meter tank 17, probe J-27 near the bottom thereof becomes wet with the result that probe relay JR-27 operates to open contacts JR-27-L1 and JR-27-L2 with no effect on the system. When the oil level wets probe J-24 the probe relay JR-24 opens contact JR-24-L and closes contact JR-24-H1, with no effect on the system, and closes contact JR-24-H2 which latches latching relay LR-4. As latching relay LR-4 latches, contact LR-4A closes with no effect other than to prepare a circuit to valve V-26. Topping out of meter tank 17 involves wetting of probe J-23 which, in turn, energizes probe relay JR-23 thereby opening contact JR-23-L with no effect other than to prevent cycling of latching relay LR-3. Contact JR-23-H closes with the result that latching relay LR-3 unlatches and contact LR-3B opens thereby closing valve V-25. As valve V-25 closes, contact V-25A opens and transfer pump 26 stops; also contact V-25-B closes with no effect on the system other than to prepare a circuit to valve V-26. As contact LR-3B opens, contact LR-3A closes thereby energizing time-delay relay TD-5 and closing contact TD-5A and after a one-minute delay valve V-24 opens. As contact LR-3A closes, latching relay LR-7 latches and contact LR-7A opens thereby charging condenser Z-2 through a 22K resistor in series with rectifier X-2. Simultaneous with latching of latching relay LR-7 latching relay LR-1 also latches thereby closing contact LR-1B with no effect on the system other than to prepare a circuit to valve V-15, and contact LR-1A opens thereby de-energizing time-delay relay TD-4 and opening contact TD-4A which closes valve V-14.

After a time interval set by time-delay relay TD-5, oil drains back to surge tank 15 through valve V-24 and meter tank 17 tops out. This topping-out of meter tank 17 involves probe J-23 becoming dry with the simultaneous opening of switch JR-23-H and closing of switch JR-23-L, both of which exert no effect on the system. When sufficient oil has drained through valve V-24 to the surge tank from outside the upper metering rim (see rim 16a of Figure 3), probe J-24 becomes dry thereby opening probe relay contact JR-24-H1 and JR-24-H2 with no effect on the system, and closing contact JR-24-L which also has no effect on the system, other than preparing the circuit to valve V-26. At this stage of the

operation meter tank 17 is now topped out and will run to pipe line as soon as meter tank 16 is empty and valve V-16 closes. As soon as meter tank 16 is empty and valve V-16 is closed, this meter tank immediately starts refilling. As meter tank 16 starts refilling, topped out meter tank 17 starts running to the pipe line, as follows: As the last of the oil leaves meter tank 16, probe J-17 becomes dry thereby energizing probe relay JR-17 to close switch JR-17-L1 which latter operation unlatches latching relay LR-6 thereby closing contact LR-6A and a run counter RC-1 is pulsed. The run counter circuit is reset so no counts can register until tank 16 has refilled and emptied. As contact JR-17-L1 closes, contact JR-17-L2 also closes with the result that latching relay LR-2 unlatches and contact LR-2A opens thereby closing valve V-16 simultaneously with which closing contact V-16-A opens, relay VR-16 de-energizes and contact VR-16-A closes after which valve 15 opens, contact V-15-A closes and transfer pump 26 starts, and contact V-15-B opens interlocking with valve V-16. Meter tank 16 is now refilling. Contact VR-16-C opens thereby de-energizing time-delay relay TD-2 and starts time-delay contact TD-2A to timing out. Contact VR-16-B also closes thereby opening valve V-26 and simultaneously closing contact V-26-A, energizing relay VR-26 thereby opening contact VR-26-A interlocking with valve V-25, and opening contact VR-26-B interlocking with valve V-16, and closing contact VR-26-C thereby re-energizing time-delay relay TD-2. Contact TD-2A remaining closed allows the pipe line pump 33 to continue to run. Meter tank 17 is now running oil to the pipe line.

Meter tank 16 is now ready for refilling, the steps being as follows: Probe J-17 becomes wet and contacts JR-17-L1 and JR-17-L2 open with no effect on the system. When the tank is substantially full and probe J-14 becomes wet, contact JR-14-L1 opens with no effect, and contact JR-14-H1 closes, also with no effect, and contact JR-14-H2 closes with the simultaneous latching of latch relay LR-2. Upon latching of this relay, contact LR-2A closes with no effect on the system other than to prepare a circuit to valve V-16.

When meter tank 16 becomes full, probe J-13 becomes wet and switch JR-13-L opens with no effect on the system other than a protection of latching relay LR-1 from cycling. Contact JR-13-H closes with the simultaneous unlatching of latching relay LR-1, and opening of contact LR-1-B with the resulting closing of valve V-15. As valve V-15 closes, contact V-15-A opens and the transfer pump stops, contact V-15-B closes with no effect on the system other than to prepare a circuit to valve V-16. As contact LR-1B opens, contact LR-1A closes with the simultaneous energizing of time-delay relay TD-4 and the closing of contact TD-4A with opening of valve V-14 after a one-minute time delay. As contact LR-1A closes, latching relay LR-6 latches and contact LR-6A opens with charging of the condenser Z-1, latching relay LR-3 latches and contact LR-3B closes with no effect on the system other than to prepare a circuit to valve V-25, and contact LR-3A opens with the simultaneous de-energizing of time-delay relay TD-5 and opening of contact TD-5A with the closing of valve V-24.

After a time interval set by time-delay relay TD-4, oil drains back to the surge tank through valve V-14 and meter tank 16 then tops out as follows: Probe J-13 becomes dry, contact JR-13-H opens and contact JR-13-L closes, these latter two operations having no effect on the system. Probe J-14 then becomes dry with the simultaneous opening of contact JR-14-H1 and JR-14-H2 with no effect on the system and closing of contact JR-14-L1 with no effect on the system other than to prepare the circuit to valve V-16. Meter tank 16 is now topped out and will run to pipe line when meter tank 17 is empty and valve V-26 is closed.

When meter tank 17 is empty, probe J-27 is dry and

contact JR-27-L2 closes with the simultaneous unlatching of latching relay LR-7, contact LR-7A closes and run counter RC-1 is pulsed. The run counter circuit is reset so that no counts can be registered until tank 17 has refilled and emptied. As contact JR-27-L2 closes, contact JR-27-L1 also closes with the simultaneous unlatching of latching relay LR-4 and opening of contact LR-4A. Following this contact opening valve 26 closes and contact V-26-A opens with the simultaneous de-energizing of valve relay VR-26, contact VR-26-A opens, valve V-25 opens, contact V-25-A closes and the transfer pump starts, contact V-25-B opens and interlocks with valve V-26 so that V-26 cannot open until the tank has become completely filled and topped out. As contact V-26-A opens, contact VR-26-C also opens and time-delay relay TD-2 energizes with the simultaneous starting of the timing out period to open contact TD-2A. Also contact VR-26-B closes with the simultaneous opening of valve V-16 and closing of contact V-16-A. Valve relay VR-16 also energizes with the simultaneous opening of contact VR-16-A interlocking with valve V-15, and opening of contact VR-16-B interlocking with valve V-26, and also closing of contact VR-26-C with the simultaneous re-energizing of time-delay relay TD-2. Contact TD-2A remaining closed allows the pipe line pump to continue to run. Meter tank 16 is now running to the pipe line, and meter tank 17 is filling. Subsequent filling and emptying of the meter tanks follows the sequence as hereinabove described.

Data for completion of a run ticket are taken once each day from the temperature-pressure recorder 37 of Figure 2, from run counters RC-1 and RC-2 of Figure 2A and from the composite oil sample stored in the sampling vessel 35 of Figure 1. The B.S. & W. content and A.P.I. gravity are determined manually from the composite oil sample. The pressure recorder serves as a double check on the run counters and provides a permanent record of the filling and running of each tank.

The function of the pressure recorder is to record the static head of liquid in the meter tanks thus indicating each complete fill and dump of each meter tank. If partial dumps occur, the volume of oil transferred can be calculated from the static head pressure recorded. The pressure recorder thus gives a complete chronological record of the oil transferred into and out of the meter tanks. The pressure record being on the same chart with the temperature record serves to correlate the temperature of the oil with the time the oil started to pipe line.

In order that the system may be manually stopped, with an integral number of dumps recorded, switch SW-2 is opened. Opening switch SW-2 causes the transfer pump 26 to stop and allows the tank which is running to the pipe line to complete its emptying portion of the cycle. The counters and recorders are then read and the system returned to operation by the manual closing of the switch SW-2.

The several motor valves of our system are normally closed, electrically operated valves. The motors of these valves require approximately 150-volt-amperes for a period of 25 seconds to open the valves completely. A solenoid pilot valve holds the main valve open against the action of the closing spring. Loss of power to the holding solenoid allows the valve to close, the time required for a closing being approximately five seconds. While the valves that we have used are as just described, it is realized that other suitable types of normally closed, electrically or pneumatically operated valves can be used.

While we have described the use and operation of capacitance probes such as J-7, J-8, etc., as liquid level sensing apparatus, it is realized that, if desired, suitable liquid level float control apparatus, such as float actuated switch assemblies similar to the float actuated switch 75 FS-6, can be used. Figure 5 illustrates the alternative

11

float switch assembly which, as stated herein, is sometimes used in place of the probes. Float 45 in tank 47 operates a switch in switch box 46 to energize and de-energize relay JR-14 to open and close contacts as illustrated in Figure 2A. Since upon closing the circuit to power leads 23 and N, the relay is immediately ready for operation and power lead 23 is beyond the time delay switch TD-1.

A conduit 18 is attached to the uppermost part of each of the two meter tanks 16 and 17 and to the surge tank 15 as well as to the boot 14 and receiver 13a for gas pressure equalization purposes. In case, however, the oil contains a considerable amount of dissolved gas, the gas which weathers or vaporizes from the oil during its handling passes through the gas equalization line to venting or to recovery, as desired. A pipe 32 leads from the bottom portion of meter tank 17 to motor valve V-26 and thence to pipe 31 for passage of oil to the pipe line pump 33.

Sampler vessel 35 is provided, as illustrated in Figure 1, for the purposes of obtaining composite samples of the crude oil being transferred. While temperature of each metered volume of crude oil is determined automatically, the B.S. & W. content and the A.P.I. gravity are determined manually, say once each day, from the composite sample of crude oil from sampler vessel 35. This sampler is of the composite sampler type and takes a small sample of oil passing through pipe 31 to the pipe line pump each time a meter tank of oil passes to the pipe line pump. Any suitable sampling device can be used, many are available commercially. A conduit 36 is connected with the upper portion of each of the meter tanks and with the surge tank 15 as an emergency overflow pipe in case the meter tanks ever fill to a level above the uppermost probes.

In the metering tank 16 of Figure 3 is inserted a temperature probe 38 which is, if desired, a thermocouple, or other temperature sensing means suitable for obtaining crude oil temperatures accurately. This temperature sensing means or probe is operatively connected to temperature-pressure recorder 37, illustrated diagrammatically in Figure 2.

The B. S. & W. content of the oil in the transfer line between the surge tank and the transfer pump is continuously indicated on a meter relay in the monitor output circuit. This meter relay has movable upper and lower limit contacts. The upper contact makes it possible to set the tolerable upper limit of B. S. & W. content. If the instrument senses B. S. & W. content above the preset limit for 30 seconds or more, the transfer pump is stopped and the circulating pump starts. Bad oil, that is, oil containing more than a predetermined quantity of water, is recirculated through the treater until the monitor indicates that contamination is below the tolerable limit. Closing of the upper limit contact also energizes a signal at the telephone P.B.X board so that operating and maintenance personnel can be informed that abnormal conditions exist.

The lower limit contact on the meter relay serves to make the capacitance monitor itself fail-safe. The meter is calibrated so that 0 (zero) contamination of the oil reads 4 divisions on the scale. The meter will only reach the lower limit contact (set at 0) when the monitor cell output signal is lost, as it would be in the case of electronic trouble.

If the transfer of oil from the surge tank to the meter tanks is stopped, for any reason, the level in the surge tank will rise above the normal high level indicated by the elevation of probe J-7, and actuate the emergency high level control probe J-8. This control energizes a light on the panel in the control house 30 and also signals the telephone P.B.X board. This same control is a safe high level control, that is, if the level control itself fails, it will close the same contact that closes when it senses

12

high level. For this reason the high level control in the surge tank serves also as the power failure signal.

The magnetic starters for the monitor pump and the transfer pump are interlocked so that the latter, that is, the transfer pump, cannot start unless the monitor pump is operating. This arrangement insures that no oil will transfer that has not been sampled by the monitor.

While the motor valves hereinbefore described in the operation of our automatic custody transfer system were described as being electrically operated motor valves, it is realized that the use of electrically operated valves is not essential because pneumatically operable diaphragm motor valves can also be used. The relays which actuate the hereinabove described motor valves can, in a pneumatic system, operate a pilot which regulates the pneumatic pressure to the diaphragm of the diaphragm operated motor valve. Diaphragm operated motor valves are, when desired, equipped with limit switches as well as are electrically operated valves.

The use of latching relays in the meter tank control system insures a proper continuation of uninterrupted operational cycles. Two of these relays are used in a special circuit for operating the run counters. Each tank must completely fill and completely empty before the counter will register.

The limit switches on the fill valve and the run valve on each meter tank are used for electrical interlocks between the valves. The fill valve and run valve on one tank cannot both be open at the same time. Also, the two run valves on the two tanks cannot be open at the same time and neither can the two fill valves on the two-meter tanks be open at the same time.

The latching relays, which control the transfer cycle, are connected through a fuse F in such a way that malfunctioning of a level control will cause this fuse to blow. Thus, if any meter tank level control fails, then within one complete cycle of the metering system (i.e., filling and dumping of both tanks) the contacts of the abnormal level control will cause one or more of the latching relays to oscillate on its own contacts thus causing fuse F to blow and de-energizing the transfer pump and all latching relays. This particular feature makes the entire system practically fool-proof and self-protected in case of failure of any of the meter tank level controls.

While we have described our automatic transfer system as being a two-meter tank system, it is realized by those skilled in the art that any number of meter tanks necessary can be used. It is merely necessary to increase correspondingly the number of apparatus parts fully disclosed relative to the two-meter tanks hereinabove described. Any number of tanks required can be intercontrolled and interregulated as well as the two tanks of our invention. In some cases it is desirable to employ two surge tanks in place of the single surge tank as herein disclosed. In case two surge tanks are used, in some cases it may be desired to have the surge tanks completely separated from one another or, if desired, the surge tanks can be interconnected with each other so as to maintain the level of liquid in both tanks the same.

In Figure 3 of the drawing is illustrated, on an enlarged scale, a suitable metering tank for use according to our invention. The tank is fully described in a pending application, Serial No. 622,863, now Patent No. 2,893,595. Briefly, tank 16, previously mentioned in the description of Figure 1, is, in general, cylindrical in shape, and is provided with a frusto-conical top and substantially an inverted conical bottom. The tank is supported by any suitable type of support desired. The bottom of the tank terminates substantially as illustrated in Figure 3, with the capacitance probe J-17 disposed at substantially the position shown. For tank volume purposes the bottom of the tank is considered as the valve V-16 and the top as rim 16a. Thus the volume, preferably in barrels of 42 gallons each is the volume between rim 16a and valve V-16. Meter vessels 16 and

17 are considered for all practical purposes constant volume vessels. Liquid which is admitted to the tank above the level indicated by rim 16a either overflows through the emergency overflow pipe 36 to the surge tank 15 or is removed through valve V-14 in the drain pipe 19 to the surge tank 15. The level controls identified in this figure as J-13 and J-14, as mentioned hereinabove, are in some instances capacitance probes, as described hereinabove, or, if desired, they are liquid level float controls. In other words, any suitable type of level indicating or sensing apparatus is used in the practice of our invention.

In the example described herein, when using capacitance probes as level sensing means, the probes J-8, J-13 and J-23 are fail-safe-high probe units. When these probes are dry, that is, not immersed in oil, a vacuum tube oscillates and energizes the corresponding relay. For example, when probe J-13 is dry, the relay JR-13 is energized, and when this probe becomes wet with oil or when there is a circuit component failure, the relay becomes de-energized.

In the example herein described capacitance probes J-7, J-14, J-17, J-24 and J-27 are fail-safe-low probe units. When these probes are dry of oil, a vacuum tube oscillation is cut off and the corresponding relay is de-energized. For example, when probe J-14 is dry, relay JR-14 is de-energized and when this probe is wet with oil, the relay JR-14 becomes energized.

The fail-safe-high and fail-safe-low probes, with their electronic circuits, are available in commerce. As mentioned herein, float switches are used, when desired, in place of the fail-safe-high and fail-safe-low capacitance probe assemblies.

In Figure 4 is illustrated diagrammatically a wiring hookup for use with a capacitance probe. In this figure reference numeral 40 identifies a master unit, that is, a master control unit in which Y-1 and Y-2 are terminals for connection with a power source, as leads 13 and N. Relay JR-14 is for operation of contacts as the relay is energized and de-energized. This relay corresponds to relay JR-14 of Figure 2A and the connections L-1, C-1, H-1; L-2, C-2 and H-2 correspond to the L-1 and L-2 low connections, the H-1 and H-2 correspond to the high connections, and C-1 and C-2 correspond to the common connections immediately below and operable with relay JR-14 of Figure 2A. Reference numeral 41 identifies the oscillator unit and reference numeral 42 the actual probe. Power source 13 and N is used for the master unit 40 in order to provide warmup time for the electronic portion of this probe assembly.

The electrical leads at the bottom of Figure 2A connect with the leads of corresponding reference numerals of Figure 2B. Thus leads 23, A, 46a, 76a, 64a, 58a, 59a, 35a, 49a, 65a, 51a, 38a, 60a, 52a, 50a, 77a, 63a, 72a, 13, 53a, 24a, 52a and N correspond to the similarly numbered electrical leads at the top of Figure 2B.

Switches SW-1, SW-6, SW-10 and SW-2 are manually operated switches.

Switch TC-1A of Figure 2A is operated by the sequence interrupter clock TC-1 of Figure 2.

Contact R6-A of Figure 2A is disposed between contacts TD-1A and coil R-1.

The arrowed connection identified in Figure 2A by the legend J-14 means that this connection is a cable leading from relay JR-14 to the probe assembly J-14. The probe assembly 48 illustrated in Figure 4 includes the capacitance probe itself identified by reference numeral 42 and the oscillator unit 41. In each of the corresponding probe relays, JR-24, JR-13, JR-23, JR-17, JR-27, JR-7 and JR-8, there is a corresponding cable which leads from the respective relay to its probe assembly.

In Figure 2 the monitor hookup to power leads 13 and N is illustrated.

For standby operation of the temperature-pressure recorder 37 and the time clock TC-1, in case of failure of

the power supply, a battery system is provided. This standby power supply (battery 102, inverter 102a, relay R-7, Figure 2) enables the temperature-pressure recorder to operate continuously, even during time of a power failure, thereby recording any change in meter tank levels that might be caused by leaking inlet or outlet valves.

Figures 2, 2A and 2B, combined, illustrate the entire system. Leads 13, N and 23 of Figure 2 are provided with legends directed to Figure 2A and lead 7 is directed to Figure 2B. In a similar manner numerous wires identified by their reference numerals in Figure 2A are intended to lead to wires of the corresponding reference numerals in Figure 2B.

The small tank illustrated in Figure 1 and carrying the legend "sump" is installed as shown to provide a sufficient volume of oil between valve V-16, or valve V-26, and the pipe line pump 33 so that the pipe line pump will not go on gas between the time probe J-17 or probe J-27 operates to shut down the pump and the time the pump actually stops. As is well known in the art, it is bad practice for a liquid transfer pump to go on gas.

Under certain specific conditions run counter RC-2 can miss a count. This specific condition exists at a time when a power failure occurs when using a valve requiring power for opening and power for closing and pipe line pressure is sufficiently low that oil from the meter tank is running to the pipe line by gravity. Upon failure of power whether the pipe line pump is used or not, oil may then flow by gravity, and when the discharging meter tank becomes empty, its counter will not be pulsed to record a count. A pipe line pump may be used to expedite transfer of meter tank oil to the pipe line even though pipe line pressure is sufficiently low for gravity flow.

In Figure 9 is illustrated apparatus for passage of metered oil from the vessel having the legend "sump" to a pipe line with a pipe line pump and without a pipe line pump. In this figure, gravity flow to pipe line is from the meter tanks of Figure 1 through pipe 31 or pipe 32 to the sump then through pipe 33b, with its valve open to pipe line, the valve in the pipe provided with pump 33 being closed.

In Figure 6 is illustrated a wiring outlay in which the run counter will not miss a count when electric power goes off during the time the meter tank is running by gravity to pipe line. Like reference numerals on Figure 6 and on Figures 2A and 2B refer to like apparatus parts. This Figure 6 shows a portion of Figure 2A with the required apparatus and wiring changes.

In Figure 6 one side of switch LR-8A goes to the manually operable switch SW-2 while the other side is connected directly to lead 23. One connection of the coil of latching relay LR-7 is connected through a resistance to a switch RC-2-XA, which, in turn, is connected directly with lead 23. The other two connections of the coil of relay LR-7 remain as shown in Figure 2A. Run counter RC-2 is connected directly to lead N and to one contact of a normally open switch LR-7XA. The other contact of switch LR-7XA is connected to the switch attached to lead 38a, shown in Figure 2B. Rectifier X2 and the resistor in series therewith and condenser Z2 illustrated in Figure 2A are omitted.

One contact of normally open switch LR-6XA is connected to one side of run counter RC-1 while the other contact of this switch leads directly to switch JR-17-L1. The rectifier X1 and the resistor in series therewith and condenser Z1, illustrated in Figure 2A, are omitted in the embodiment illustrated in Figure 6. The lead from the coil of latching relay LR-6, which in Figure 2A led by way of the resistor to switch JR-17-L1, is disconnected from this switch and connected through the resistor to one contact of a switch RC-1-XA. The other contact of this switch RC-1-XA is connected directly with lead 23.

In the operation of the embodiment illustrated in Figure 6, when meter tank 16 is full, probe J-13 is wet and probe relay JR-13 (Figures 2A and 2B) closes contact JR-13-H which closing completes a circuit through the coil of latching relay LR-6 which latches. The normally open switch LR-6XA is latched closed and thus prepares the circuit to the counter RC-1. When meter tank 16 tops out, probe J-13 becomes dry and probe relay JR-13 opens contact JR-13-H with no effect on the circuit. Probe J-14 becomes dry and probe relay JR-14-L closes thereby causing valve V-16 to open so the meter tank 16 can run to pipe line (Figures 2A and 1). When meter tank 16 becomes empty, probe J-17 becomes dry and probe relay JR-17 actuates to close contact JR-17-L1, which closing energizes a coil in run counter RC-1 thereby recording a count and closing switch RC-1-XA and unlatching relay LR-6. Upon unlatching of relay LR-6, switch LR-6XA opens.

When meter tank 17 is full and valve V-16 at the bottom of meter tank 16 is closed, probe J-23 is wet and probe relay JR-23 closes contact JR-23-H which closing completes a circuit through the coil of latching relay LR-7 which latches. The normally open switch LR-7XA is latched closed and thus prepares the circuit through the run counter RC-2. When meter tank 17 tops out, probe J-23 becomes dry and probe relay JR-23 opens contact JR-23-H with no effect on the circuit. Probe J-24 becomes dry and probe relay JR-24-L closes thereby causing valve V-26 to open so meter tank 17 can run to pipe line (Figures 2A and 1). When meter tank 17 becomes empty, probe J-27 becomes dry and probe relay JR-27 actuates to close contact JR-27-L2 which closing energizes a coil in run counter RC-2 thereby recording a count and closing switch RC-2-XA and unlatching relay LR-7. Upon unlatching of relay LR-7, switch LR-7XA opens.

If oil is running from either meter tank by gravity to pipe line when electric power fails, the respective run valve (V-16 or V-26) which requires power for opening and power for closing, remains open and the tank goes empty. Probe J-17 goes dry during the power outage, contact JR-17-L1 will be closed when power is restored and the counter will be pulsed and, in turn, will close switch RC-1-XA to unlatch latching relay LR-6 and continue the cycle.

If either meter tank, as, for example, meter tank 16, has not completely filled and some malfunction allows the oil to run out, a count will not occur because contact JR-13-H will not close and switch LR-6XA will not be closed.

Power fluctuations cannot pulse counter RC-1, or RC-2, because there is a complete circuit to the coil of the counter only during the instant that the counter solenoid is energized. Once the solenoid plunger reaches the top of its stroke, switch RC-1-XA or RC-2-XA closes thereby unlatching the relay LR-6 or LR-7 and causing switch LR-6XA or LR-7XA to open.

Our automatic transfer system has been hereinbefore described as being a two-meter tank system with any number of meter tanks necessary being used. This term "any number of meter tanks" includes one meter tank as well as systems containing two, three or even more meter tanks.

The description of a one-meter tank system, illustrated in Figures 7, 8a and 8b, which follows, will start with the surge tank 15 being empty, the control system de-energized, all latching relays in their unlatched position, a hydraulically operated motor valve XV-4 being closed, and a meter tank 101 empty. Many of the pieces of equipment in this one-meter tank system are similar to corresponding pieces of the two-tank system described hereinbefore, and like pieces of apparatus are identified by like reference characters.

In Figure 7 there are illustrated several improvements over the transfer system illustrated in Figure 1. The

main point in the embodiment of Figure 7 is that only one-meter tank is required. Such a system as a one-meter tank system is especially adaptable for small production leases, and even for large production leases because the sump tank provides for continuous transfer to pipe line.

In Figure 7 oil from a lease production header, not shown, enters the system through pipe 11. This oil is treated in boot 14, settled in receiver 13a, gas vented in pipe 18 and water withdrawn in pipe 12 as explained relative to Figure 1. Likewise, oil of reduced B.S. & W. content is passed from receiver 13a through pipe 20 into surge tank 15 from which oil is circulated through pipes 21 and 27 to and from monitor cell 29 in control house 30 by pump 28, also as previously explained. A suitable capacitance cell for use in this monitoring operation is disclosed hereinbefore. The monitor cell 29 continuously indicates B.S. & W. content of the oil and upon increase of B.S. & W. content above a predetermined limit, as 0.5 percent, the monitor functions to shut down transfer pump 26, start circulating pump 25 with oil being recirculated to the booth until the monitor indicates 0.5 percent or less B.S. & W. When the B.S. & W. has been lowered to a value below the upper limit, the circulating pump 25 stops, and transfer pump 26 starts, all in response to action of the monitor, also as explained hereinbefore. When transferring oil to a pipe line, not shown, using a pump, as pump 33, the oil passes from tank 104 through a pipe provided with pump 33. When transferring oil to a pipe line by gravity flow, the oil passes from tank 104 through pipe 33a to a pipe line, not shown.

A low level float XL-1, a normal high or working level float XL-2 and an emergency high level float XL-3 operate for regulating liquid flow in the same manner as probes FS-6, J-7 and J-8 of Figure 1. It is to be noted that there is not a motor valve in a transfer pipe 102; instead, pipe 102 adjacent the meter tank 101 is an inverted U-shaped pipe with a siphon breaker 106. This siphon breaker 106 communicates with vent pipe 18. The horizontal portion of the U-shaped pipe is sufficiently high that the pump 26 must operate to transfer oil from the surge tank to the meter tank and that oil will not flow by gravity from the meter tank to the surge tank, and the siphon breaker is provided so that oil will not siphon from the meter tank to the surge tank. The meter tank 101 can, if desired, be similar to meter tanks 16 and 17, or it can be of other configuration, provided, of course, that its volume can be accurately determined.

When filling the meter tank, motor valve XV-4, which is any suitable hydraulic or pneumatic motor valve which requires power for opening and power for closing, is closed. When a float XL-6, in dome 111 of the meter tank, becomes wet, pump 26 stops and oil above and outside a weir 105 drains through pipe 103 to the surge tank.

Upon drainage of oil from outside of weir 105 float XL-6 becomes dry and then valve XV-4 opens and pipe line pump 33 starts. This pipe line pump is used for pipe line pressure requirements. In some cases, the oil passes through the pipe line by gravity flow from the meter tank and in this case the pipe line pump is not required.

The purpose of the sump tank, which is not a volume calibrated tank as is the meter tank, is to provide for continuous oil flow to pipe line while the meter tank is filling and topping out. When, for example, the meter tank is a 25-barrel capacity tank, it is preferred that the sump tank be of about 15 barrels capacity. The drain pipe 112 and valve XV-4 are large so that the meter tank can drain quickly to fill the sump tank even though the sump tank contents are going by gravity flow or by pump to the pipe line. In this manner, by or before the time the meter tank is empty, the sump tank 104 is full so that a maximum length of time is available for the next filling and topping out of the meter tank. It

is intended that the oil level in the sump tank should be at least some short distance above the level of float XL-4 by the time the next charge from the meter tank is ready for transfer to the pipe line. In this manner there is continuous gravity flow or pumping of oil to the pipe line. A vent line 110 is provided for passage of vapor to and from the sump tank as required by its emptying and filling. When float XL-4 becomes dry, the pipe line pump stops.

In case a pipe line pump is not required, i.e., when there is gravity flow of oil from the sump tank to the pipe line, the circuit in Figure 8 carrying the legend "pipe line circuit" is not required.

On referring to Figures 8a and 8b, upon closing a two-pole disconnect switch X-3, the primary coil of a transformer X-4 which is connected across lines XL-1 and XL-2 of a three-phase 440 volt power supply X-1, is energized. The coil of a relay XR-2, connected across lines XL-2 and XL-3, is also energized. This relay protects the motors from single phase operation when disconnect switch X-2 is closed by opening a contact XR-2A in the control circuit X-23, XH and XN when line XL-3 is open. If line XL-1 or XL-2 is open, the control circuits will be dead because there is no voltage across the control transformer. All motor starters have 110 volt coils and are operated directly from the control system. The B.S. & W. monitor 29 is energized when the two-pole fused disconnect switch X-3 is closed. The monitor is preferably a capacitance cell as hereinbefore stated.

Upon closing a master control switch XSW2, the system is energized for automatic operation and monitor pump 28 starts thereby circulating oil from the bottom of the surge tank 15 through the monitor 29 and back into the surge tank via pipes 21 and 27. Production is admitted from receiver 13a into the surge tank 15. When oil reaches a low level, float XL-1 becomes wet and switch XL-1A opens with no effect on the system. When production oil reaches a normal high or working level, float XL-2 becomes wet and contact XL-2A closes causing coil XLR1-L in latching relay XLR1 to energize and close the normally open relay contact XLR1-A. This contact closing starts the transfer pump 26 with the simultaneous closing of contacts XTP-A which energizes a pipe line sampler 35. As contacts XTP-A close, a transfer pump red light XRL4 flashes on. Also, latching of relay XLR1 causes normally open contacts XLR1-B to close thereby turning on a transfer red light XRL2, and normally closed contacts XLR1-B to open thereby turning off a refill light XRL3. The transfer pump 26 pumps oil at a greater rate than the production; thus the oil level in the surge tank 15 falls slowly. Float XL-2 then becomes dry and the latch coil XLR1-L of latching relay XLR1 becomes de-energized with no effect on the system.

The pipe line sampler 35 is placed in the position shown in Figure 7 because sufficient crude oil pressure is available at the discharge of the transfer pump to assure proper sampling.

While meter tank 101 is filling, float XL-5 is wet and switch XL-5A opens with no effect on the system. When the meter tank becomes full, float XL-6 becomes wet and switch XL-6A closes, after which time-delay relay XTD1 becomes energized and after a 30-second time delay contacts XTD1-A close and then XLR2-L energizes. As relay XLR2 latches, normally open contacts XLR2-A close (no effect on system), normally closed contacts XLR2-B open and transfer pump 26 stops. Simultaneously, with the stopping of the transfer pump, transfer pump contacts XTP-A open; then pipe line sampler is de-energized, and transfer red light XRL2 goes off. Simultaneously with opening of contacts XLR2-B, normally open contacts XLR2-C are closed which closing prepares circuit to a run counter XRC; normally open contacts XLR2-D close, which closing energizes a coil on relay XR6, closes normally open contacts XR6-A, opens nor-

mally closed contacts XR6-A, closes normally open contacts XR6-B and opens normally closed contacts XR6-B; all of these latter changes prepare a circuit to valve XV-4.

At the time float XL-6 becomes wet, switch XL-6B opens with no effect on the system. The meter tank tops out by oil draining back to the surge tank 15 until float XL-6 becomes dry. This float is placed some little distance below the edge of weir 105. When the oil outside the weir drains down sufficiently that the float becomes dry, switch XL-6A opens and as a result the coil of the time-delay relay XTD1 becomes de-energized, contacts XTD1-A open after which the latch coil of latching relay XLR2 is de-energized with no effect on the system. As switch XL-6A opens, switch XL-6B closes and coil of relay XR4 becomes energized and normally open contacts XR4-A close, followed by opening of valve XV-4 and pressure switch XPS-A opens (pressure switch on valve XV-4 that pressures up (opens) as the valve approaches its open position and closes as the valve approaches its closed position). As pressure switch XPS-A opens, pressure XPS-B closes (pressure switch on valve XV-4 that pressures up (opens) as valve approaches its closed position and closes as the valve approaches its open position). After XPS-B closes, coil of relay XR5 is energized along with closing of contacts XRS-A, this latter operation preparing a circuit for closing valve XV-4.

As the oil passes from meter tank 101 into sump tank 104 (and ultimately to the pipe line pump 33), the meter tank is considered empty at the time float XL-5 becomes dry. As float XL-5 becomes dry, switch XL-5A closes energizing time-delay relay XTD2; after a preset delay (30 seconds) contact XTD2-A closes; then run counter solenoid energizes and makes one count. As the run counter solenoid is energized, run counter switch XRC-A closes and then latching relay XLR2 unlatches and contacts XLR2-A open with no effect on the system; contacts XLR2-B close after which closing transfer pump 26 starts, contacts XTP-A close and pipe line sampler becomes energized, transfer pump red light XRL4 lights. Contacts XLR2-C open, the run counter XRC solenoid de-energizes, run counter contacts or switch XRC-A open. Normally open contacts XLR2-D open, coil of relay XR6 is de-energized, normally open contacts XR6-A opens, normally closed contacts XR6-B close, normally open contacts XR6-B open and normally closed contacts XR6-B close, and finally valve XV-4 closes.

A preset counter XPC is provided for closing off the system when a predetermined number of meter tank fulls of oil has been delivered to the pipe line, as determined by crude oil allowables.

The sequence of steps including filling of the meter tank 101, topping out of the meter tank, running of oil from the meter tank to pipe line by way of the sump tank until the meter tank is empty (oil level below float XL-5) continues until such time as the low level float XL-1 in the surge tank 15 becomes dry.

The system illustrated in Figures 7, 8a and 8b is so arranged that the transfer cycle of oil from the surge tank 15 to the meter tank 101 ends and the meter tank refill cycle begins only after a complete previous filling of the meter tank; that is, when oil in the surge tank is lowered to the level of float XL-1 while the meter tank is being filled, contact XL-1A prepares the circuit to stop transfer of oil from the surge tank to the meter tank for refilling the surge tank but this operation does not occur until the meter tank filling has been completed. In this manner a part meter tank of oil is never left standing during filling of the surge tank. To facilitate this type of operation the float XL-1 is positioned in the surge tank so that at least one meter tank volume of oil is stored between float XL-1 and the transfer pump connection. When float XL-1 becomes dry, switch XL-1A closes with no effect on the system. However, if the meter tank is filling, it continues to fill, when float XL-6 becomes wet contact XL-6A closes energizing XTD1 which closes

XTD1-A to latch relay XLR2, contact XLR2-B opens to stop the transfer pump in the usual manner. Contact XLR2-A closes causing XLR1 to unlatch, normally open contacts XLR1-A open and prevent the transfer pump restarting until the surge tank is refilled to level XL-2. Simultaneous with the stopping of the transfer pump normally open transfer pump contacts XTP-A open and pipe line sampler is de-energized, and a transfer pump red light XLR4 turns off. When contacts XLR1-A open, normally open contacts XLR1-B open and transfer light XRL2 goes off, and normally closed contacts XLR1-B close and refill light XRL3 goes on to indicate the surge tank is refilling. The system will not start transferring oil to the meter tank 101 until the oil level in surge tank 15 has risen to the level of float XL-2. When float XL-2 becomes wet, the meter tank 101 starts filling as hereinbefore explained.

When bad oil, that is, oil having a higher B.S. & W. content than desired for pipe line purposes, is noted by the monitor, normally open monitor relay contacts XMR2-A close and a monitor time-delay relay XMTD is energized (30 seconds delay) and contacts XMTD-A on this latter relay close and a relay XMR3 in the monitor is energized. As this relay XMR3 is energized, contacts XMR3-A open and the transfer pump stops, contacts XTP-A open and pipe line sampler becomes de-energized; contacts XMR3-B close and a suitable reset timer resets; contacts XMR3-C close, circulating pump 25 starts, contacts XCP-A close and a solenoid of a chemical feeder is energized; and contacts XMR3-D open.

When the oil passing through the monitor from the surge tank is again merchantable, the monitor meter hand breaks contact with the upper setting on the dial and contacts XMR2-A open with de-energizing of the monitor time-delay relay XMTD. As this latter relay is de-energized, contacts XMTD-A open and relay XMR3 is de-energized with the simultaneous closing of contacts XMR3-A, transfer pump then starts, contacts XMR3-B open, timer XT starts timing out; contacts XMR3-C open and contacts XMR3-D close; this latter operation transfers circulating pump control to the timer to keep the pump running; and when the timer times out, the circulating pump stops, contacts XCP-A open and the chemical feeder solenoid valve is de-energized. If bad oil reoccurs while the timer XT is timing out, the timer will reset and discontinue timing while contacts XMR3-C maintain the circulation pump energized. When oil is again merchantable, the circulating pump 25 remains on until the timer XT times out. The timer then does not reset until the next bad oil signal occurs.

If conditions should occur that float XL-2 becomes wet and transfer of oil to the meter tank does not begin due to continuing bad oil or system failure, the emergency high level float XL-3 becomes wet and actuates a surge tank high level warning light. In operation, float XL-3 becomes wet and switch XL-3A closes and a surge tank high level alarm light XL on a tall pole and a surge tank high level pilot light XPL go on. When transfer of oil is resumed, the float XL-3 becomes dry and de-energizes the alarm lights.

Time-delay relay XTD2 is actuated when float XL-5 becomes dry to begin a predetermined delay time, after which normally open contact XTD2-A closes to pulse the run counter XRC and the preset counter, in case the latter is used, and to close valve XV-4 to allow drainage from the walls of the meter tank before valve XV-4 closes. Red light XRL1 indicates flow of oil to pipe line when lit.

When pipe line pump 33 is used (nongravity flow), a float XL-4 in the lower portion of the sump tank on becoming dry actuates a switch XL-4A to close off the pipe line pump before the tank is empty so the pump will not go on gas. A time clock XTC-2 is provided to regulate the transfer of oil to the pipe line in case the sys-

tem can pump oil into the pipe line only between certain hours.

A pressure switch XPS-1 is provided to close down the pipe line pump in case the pipe line pressure is ever higher than a predetermined maximum pump delivery pressure. A normally open relay contact XMR2-B closes as monitor detects bad oil thereby turning on bad oil red light XLR-5. Switch XV-4A is a normally closed limit switch on valve XV-4 and this limit switch opens so that the transfer pump 26 cannot pump oil into the meter tank any time valve XV-4 is open. XMR1-A is a normally closed contact actuated to open and shut down the transfer pump 26 at any time that the monitor fails, while switch XMR1-B closes when the monitor fails thereby turning on an instrument failure red light XRL-6. The switches XMR1-A, XMR1-B, XMR2-A, XMR2-B, XMR3-A, XMR3-B, XMR3-C and XMR3-D are all operated in response to a meter relay XMR having upper and lower limit contacts and actuated by the monitor electronics.

Overload switches XOL are provided in the monitor pump 28 circuit, in the transfer pump 26 circuit and in the circulating pump 25 circuit for protection of the respective electric motors.

The embodiment illustrated in Figures 7, 8a and 8b has numerous special advantages among which are (1) if the meter tank has not completely filled and some malfunction allows the oil to run out, as to pipe line by gravity or a broken pipe or valve at the bottom of the meter tank, no count will occur because contacts XL-6A will not close and contacts XLR2-D will not be closed; (2) power fluctuations cannot pulse the counter because there is a complete circuit to the coil only during the instant that the count solenoid is energized; once the plunger reaches the top of its stroke, contact XRC-A closes causing relay XLR2 to unlatch and contact XLR2-C to open; (3) if the oil is running by gravity to pipe line when power fails, the run valve XV-4 remains open and the meter tank goes empty; closing of switch XL-5A will have no effect on the system at that time, but the instant power is restored the counter will be pulsed which pulsing in turn will close the run counter switch XRC-A to unlatch latching relay XLR2 and continue the cycle; and (4) the embodiment illustrated in Figures 7, 8a and 8b shows that the pulse counter is also fail-safe in that if the counter does not pulse when energized, then switch XRC-A will not close and latching relay XLR2 will remain latched. With relay XLR2 latched, the run valve XV-4 cannot close and the transfer pump cannot start.

The embodiment illustrated in Figures 7, 8a and 8b is much less expensive to construct and to operate than a two-meter tank system. Maintenance costs are likewise less than in the two-meter tank system.

If desired, two floats or capacitance probes can be used in the sump tank in Figure 7, the upper one serving to start a pipe line pump and the lower one serving to stop the pump so it will not go on gas. If desired, two floats or capacitance probes can be used in the dome of the meter tank of Figure 7, as illustrated in Figure 1. Furthermore, if desired, the upper float or probe in the surge tank in either embodiment disclosed herein can be set up to shut in production from the lease in case the upper float or probe, such as an emergency high level float or probe, becomes wet. This emergency high level float or probe can, however, merely turn on a signal light, ring a bell or provide other type of warning to an operator or to a P.B.X telephone switch board operating in the vicinity. Also, a pipe line pump can be regulated with only a single float or probe in the lower portion of the sump tank, as herein disclosed.

While certain embodiments of the invention have been described for illustrative purposes, the invention obviously is not limited thereto.

We claim:

1. A system for transferring known volumes of hydrocarbon liquid of predetermined quality from a source to a point of disposal comprising, in combination, a treating vessel for said hydrocarbon liquid, a surge vessel for receiving treated hydrocarbon liquid, a meter vessel of known volume, first and second conduits communicating said treating vessel with said surge vessel, a first pump in said second conduit for transmitting liquid from said surge vessel to said treating vessel, a third conduit communicating said surge vessel with said meter vessel, a second pump in said third conduit, a fourth conduit communicating the bottom of said meter vessel with a point of disposal, a monitor assembly for controlling quality of said hydrocarbon liquid, said monitor assembly comprising a monitor for sensing B. S. and W content of the hydrocarbon liquid, conduit means for passage of hydrocarbon liquid from said surge vessel to said monitor and return to said surge vessel, first and second motor valves in aid second and third conduits respectively, a first electrical circuit communicating said monitor with said first pump and with said first motor valve, a second electrical circuit communicating said monitor with said second pump and with said second motor valve, said monitor assembly being adapted to close said second motor valve and to close off electric current to the motor of said second pump to stop same and to open said first motor valve and to close the circuit to the motor of said first pump to start same when said monitor senses a B. S. and W content in the hydrocarbon liquid flowing therethrough higher than a predetermined B. S. and W content.

2. In the system of claim 1, a third motor valve and a third transfer pump in said fourth conduit, and an interlocking electrical relay circuit including said second motor valve and said third motor valve, said interlocking relay circuit being adapted to open said second motor valve only when said third motor valve is closed and to open said third motor valve only when said second motor valve is closed.

3. In the system of claim 2, a dome disposed fluid-tight to the top portion of said meter tank, the top of said meter tank being open and extending into said dome, a first liquid level sensing means in said dome above the top of said meter tank, a second liquid level sensing means in said dome and outside said meter tank at a level below the top of said meter tank, a fifth conduit for draining liquid from said dome, a fourth motor valve in said fifth conduit, a fourth electrical circuit communicating said second liquid level sensing means with said third pump and said third motor valve, a fifth electrical circuit communicating said first liquid level sensing means with said second pump and with said second motor valve, said fifth electrical circuit being adapted to close off electric current to said second pump to stop same and to close off said second motor valve upon sensing of level of liquid by said first liquid level sensing means, said fifth electrical circuit comprising a time delay relay, said time delay relay communicating with said fourth motor valve to open same after a predetermined time delay of said time delay relay thereby allowing drainage of hydrocarbon liquid from said dome, and said fourth electrical circuit being adapted to open said third motor valve and to start said third pump upon lowering of the liquid level below said second liquid level sensing means, a third liquid level sensing means in approximately the bottom of said meter tank, a sixth electrical circuit communicating said third liquid level sensing means with said third motor valve and with said third pump, said sixth electrical circuit being adapted to close said third motor valve and to stop said third pump upon drop of liquid level below said third liquid level sensing means.

4. A method for transferring a known volume of a hydrocarbon liquid having less than a predetermined concentration of B. S. and W. to a point of delivery, com-

prising the steps of receiving said liquid containing B. S. and W. in a receiving zone, treating said liquid in said receiving zone to remove at least a portion of said B. S. and W., withdrawing an aqueous phase from said receiving zone, passing liquid of reduced B. S. and W. content to a surge zone, maintaining the B. S. and W. content of said liquid in said surge zone below a predetermined value by continuously withdrawing a stream of said liquid from said surge zone, passing this withdrawn stream through a B. S. and W. sensing monitor and returning the stream to said surge zone, upon sensing a B. S. and W. content higher than the predetermined value recycling liquid from said surge zone to said receiving zone, passing only liquid having a less B. S. and W. content than said predetermined content from said surge zone to a metering zone of predetermined volume until said metering zone is completely full, then passing said liquid from said metering zone to said point of delivery.

5. A method for transferring known volumes of a hydrocarbon liquid having less than a predetermined concentration of B. S. and W. in the form of an emulsion to a point of delivery, comprising the steps of receiving said liquid containing B. S. and W. in the form of an emulsion into a receiving zone, treating said liquid in said receiving zone for breaking said emulsion whereby B. S. and W. settles to the bottom thereof as an aqueous phase thereby leaving a supernatant hydrocarbon liquid phase of reduced B. S. and W. content, withdrawing said aqueous phase from said receiving zone, passing said hydrocarbon liquid of reduced B. S. and W. content to a surge zone, maintaining the B. S. and W. content of said liquid in said surge zone below a predetermined B. S. and W. content by continuously withdrawing a stream of said liquid from said surge zone, passing this withdrawn stream through a B. S. and W. sensing monitor and returning the stream to said surge zone, upon sensing by said monitor of a B. S. and W. content higher than said predetermined B. S. and W. content recycling liquid from said surge zone into said receiving zone, passing only liquid of less than said predetermined B. S. and W. content into a first metering zone of predetermined volume until completely full, passing said liquid from said first metering zone to said point of delivery and simultaneously passing liquid from said surge zone into a second metering zone of predetermined volume, when said second zone is completely full of liquid and said first zone is empty of liquid, passing liquid from said second metering zone to said point of delivery and simultaneously filling said first metering zone with said liquid from said surge zone.

6. A system for continuously transferring known volumes of hydrocarbon liquid from a source to a point of delivery comprising a first vessel, a second vessel of known volume, a first conduit for passage of liquid from said first vessel to said second vessel, said first conduit including an inverted U-shaped tube, at least a portion of the inverted U-shaped tube being disposed at a higher elevation than the uppermost portion of said second vessel, a siphon breaker in communication with the upper portion of said inverted U-shaped tube, a third vessel of volume of at least about half that of said second vessel for delivery of said liquid to said point of delivery, said third vessel being disposed below said second vessel, a second conduit communicating the bottom of said second vessel with said third vessel for gravity flow of liquid, said second conduit being adapted to pass liquid at a more rapid rate than said third vessel delivers liquid to said point of delivery, said first conduit being adapted to pass liquid at a sufficiently rapid rate to fill said second vessel before a full third vessel of liquid passes from said third vessel to said point of delivery, means for monitoring impurity in said liquid from said first vessel, third and fourth conduits communicating said first vessel with said means for monitoring for passage of liquid from said first vessel to said means for monitoring and return to said first vessel, said means being adapted to terminate passage of liquid

in said first conduit when said monitor indicates an impurity content greater than a predetermined impurity content; and to start flow of liquid in said first conduit when said monitor indicates impurity content less than said predetermined impurity content, and means for recording the number of full second vessels of liquid passed to said third vessel and to said point of delivery.

7. A system for transferring known volumes of hydrocarbon liquid of predetermined quality from a source to a point of disposal comprising, in combination, a treating vessel for said hydrocarbon liquid, a surge vessel for receiving treated hydrocarbon liquid, first and second conduits communicating said treating vessel with said surge vessel, a first pump in said second conduit for transmitting liquid from said surge vessel to said treating vessel, a meter vessel of known volume, a third conduit communicating said surge vessel with said meter vessel, a second pump in said third conduit, a fourth conduit communicating said meter vessel with a point of disposal, a monitor assembly for regulating quality of said hydrocarbon liquid, said monitor assembly including a monitor for sensing B. S. and W. content of the hydrocarbon liquid, means for passage of hydrocarbon liquid from said surge vessel to said monitor and return to said surge vessel, a first electrical circuit communicating said monitor with said first pump, a second electrical circuit communicating said monitor with said second pump, said monitor assembly being adapted to open the circuit to the motor of said second pump to stop same and to close the circuit to the motor of said first pump to start same upon sensing by said monitor of a B. S. and W. content in the hydrocarbon liquid flowing therethrough higher than a predetermined B. S. and W. content.

8. A system for transferring known volumes of hydro-carbon liquid of predetermined quality as regards B. S. and W. content from a source to a point of disposal comprising, in combination, a vessel for receiving treated hydrocarbon liquid, a meter vessel of known volume, a first conduit communicating the receiving vessel with the meter vessel, a first electric motor driven pump in said first conduit, a second conduit communicating said meter vessel with a point of disposal, a B. S. and W. detecting monitor, a third conduit communicating the receiving vessel with said monitor, a fourth conduit communicating said monitor with said receiving vessel, a second pump in said third conduit for pumping hydrocarbon liquid from the receiving vessel through said monitor and return to the receiving vessel, an electrical circuit communicating said monitor with the motor of said first pump, said monitor being adapted to open said electrical circuit thereby stopping said first pump upon sensing a predetermined high B. S. and W. content.

20 9. In the system of claim 8, said first conduit including an inverted U-tube, said U-tube being disposed at the end of said first conduit communicating with said meter vessel in such a manner that the discharge end thereof extends into said meter vessel from a level higher than 25 the top level of said receiving tank, a tube having an upper end open and its lower end communicating with said U-tube in such a manner that said open end extends to a higher elevation than the elevation of said U-tube.
